UNITED STATES PATENT OFFICE.

HARRY PFANNENSTIEHL, OF MAPLEWOOD, NEW JERSEY, ASSIGNOR TO WESTERN ELECTRIC COMPANY, INCORPORATED, OF NEW YORK, N. Y., A CORPORATION OF NEW YORK.

SELECTING MECHANISM.

Application filed November 16, 1921. Serial No. 515,443.

To all whom it may concern:

Be it known that I, HARRY PFANNENSTIEHL, a citizen of the United States, residing at Maplewood, in the county of Essex, 5 State of New Jersey, have invented certain new and useful Improvements in Selecting Mechanisms, of which the following is a full, clear, concise, and exact description.

This invention relates to selecting mechanism and particularly to selecting mechanism of the manually controlled type.

An object of the invention is a selecting mechanism and a distributing mechanism utilizing a single movable transmitting contact combined in a unitary structure.

Another object is an arrangement wherein the code combinations of message impulses are transmitted to a line conductor solely through the instrumentality of mechanical movements.

Another object of the invention is to provide a selecting mechanism which is simple in construction, positive reliable and efficient in operation.

In accordance with the above objects the present invention contemplates the provision of manually operated keys, which co-operate with slidable members or bars adapted to be moved from their normal positions of rest whereby rocker arms are positioned selectively, and which are arranged to be actuated consecutively by cams to vibrate a single transmitting contact.

Referring to the drawings:

Fig. 1 shows a partial plan view of a keyboard with the selecting elements and the distributing mechanism.

Fig. 2 is a sectional view taken along the broken line 2—2 of Fig. 1.

Fig. 3 shows the mechanism, illustrated in Fig. 2, in a different operative position.

Figs. 4 and 5 are sectional views taken along the broken line 4—4 of Fig. 1 and show the selecting and selectable elements in their non-selecting and selecting positions, respectively.

Fig. 6 is a perspective of a portion of the apparatus shown in Fig. 1.

In the illustrated embodiment of the invention, the keyboard is arranged like the keyboard of an ordinary typewriter, each key being capable of independently performing the selecting operations required to position selectable elements to produce the desired selecting operations. Each key lever

7 is pivoted to the frame 8 and is provided with springs 9 normally tending to elevate the outer end thereof. The springs and pivots, although not shown in detail, are similar in construction to the arrangement disclosed in Patent No. 1,229,201, issued June 5, 1917. Each key lever has towards the rear thereof a knife-like portion 6 serving to move upon the actuation thereof the selecting elements in varying combinations.

Situated directly above and extending in a direction transverse to the key levers 7 are six slidable selecting members 11, 12, 13, 14, 15 and 16 and a stationary member 17. The frame 8 is provided with slotted members 18 and 19 which serve to support and guide the members 11 to 16 inclusive. Each of the selecting members 11 to 16 inclusive has thereon a different arrangement of downwardly projecting beveled edges 20, so that these members will be moved in varying combinations according to the key lever depressed. When any one of the key levers is depressed the knife edge 6 engages the beveled projections 20 on the selecting members so that these members will be moved in a direction transverse to the position of the key levers in accordance with a predetermined arrangement. The selecting member 11, however, moves upon the depression of any one of the key levers 7 for effecting certain selecting operations, and is provided at one extremity thereof with a stop 21 and a member 22 mounted just above the stop arm 21, one surface of which is inclined slightly.

Each of the selecting members 12 to 16 inclusive have notches 23 cut on the upper surface and at one end thereof and in which an operating link normally rests, there being an operating link individual to each one of these bars. The operating links 28 to 33 inclusive are pivoted to a revolvable bail 34 supported by arms 35 and 36, which are in turn, fixed on a rod 37.

Situated directly beneath the other end of the operating links 28 to 33 are a series of cams 44 spaced equally distant along a shaft 39 and separated by metal discs 25, so that upon rotation of the shaft the operating links will be engaged by their associated cam for effecting their movement consecutively. The cams and metal discs are held in position by means of bushings 38 and 46 which are rigidly secured to the shaft 39. Nor-

mally, the shaft 39, having secured on one extremity thereof a beveled gear 40, tends to rotate by power communicated thereto from a motor 41 driving a beveled gear 42, 5 through a slip friction clutch but is restrained against motion by the stop arm 43 rigidly secured to the shaft 39 engaging the stop 21, which, as previously described, is secured to the selecting member 11.

10 Mounted directly above bail 34 and in a position central thereto and arranged to be engaged by a circular disc 27 is a single transmitting contact 45. This contact 45, when the shaft 39 is at rest, engages a contact screw 47 owing to the bail 34 being raised on account of one end of the operating link 33 being fulcrumed on the member 17 and the other end thereof in engagement with the associated cam on the shaft 39.

15 The contact spring 45 is also provided with a contact terminal 48 which may be either connected directly to battery or ground, as the case may be, or through the winding of a selecting magnet 60 of a printer, while 20 the contact 47 is permanently connected to the line conductor 61 extending to a distant station, and over which it is desired to transmit the desired code combinations of message impulses in accordance with the depression of the desired key lever 7. Moreover the double polarity system may be 25 used with equally good results, in which the contact spring is normally in contact with marking battery while spacing battery is 30 connected with the opposite contact, in that the contact may be moved to change the polarity to the current applied to the line conductor.

35 At a point intermediate the ends of the selectable members 12 to 16 inclusive, a pair of notches 50 and 51 are cut, the intervening portion thereof being formed in the shape of a knife-edge to more readily permit of the movement of a downwardly and horizontally projecting portion 56 of a locking bar 52. Bar 52 is pivoted to the frame at 53 and has an extending portion thereof which is arranged to be engaged by a cam 55 on the shaft 39 as shown in Fig. 2. During 40 the period that the shaft 39 is at rest the projecting portion 56 of the member 52 is withdrawn from the slots 50 and 51, thereby permitting of their movement. However, the instant that the shaft is set in rotation 45 the projecting portion 56 due to the cam 55 being moved out of engagement therewith and the action of a coiled spring 54, is drawn into engagement with the slots 50 or 51, depending upon the position of the 50 selecting members 12 to 16 inclusive, thereby locking the members in position to prevent the depression of one of the key levers 7 while the shaft 39 is rotating and consequently the mutilation of signals.

55 The operation of the structure just de-

scribed is as follows: Assume that one of the key levers 7 has been depressed, the common member 11 is moved in the direction of the arrow thereby moving the stop 21 out of the path of the stop arm 43, and since power is communicated to the shaft 39 through a slip friction clutch, this shaft will be revolved. As previously stated, the contact spring 45 is normally in engagement with the contact 47. However, the instant the shaft 39 is set in rotation the cam associated with the operating link 33 moves out of the path thereof thereby allowing the bail 34 with the disc 27 to drop and consequently open the circuit between contact spring 45 and contact 47, thus transmitting what is known as a start impulse. Also immediately following the setting of the shaft 39 into rotation, the member 52 is moved so that the projection 56 engages one or the other of the notches 50 and 51 in the selecting members 12 to 16 inclusive, depending upon the position of these members, thereby preventing their movement until the present selection has been cleared out. Let it also for the sake of clearness be assumed that the selecting members 12, 14 and 16 have been moved in the direction of the arrow, while the remaining selecting members remain in the opposite position. As the shaft 39 continues its rotation, the selecting member 12 having been moved in the direction of the arrow, causes the end of the operating link 28 to rest upon the upper surface of the bar 12. Upon the engagement of the associated cam with the link 28, this link will be fulcrumed on bar 12, thereby raising the bail 34 and effecting a closure between the contact spring 45 and the contact 47. A condition similar to the one described in connection with the selecting member 12 will, however, be established upon the engagement of the cams individual to the operating links 30 and 32, respectively, as the selecting members are moved so as to form a fulcrum for their respective operating links.

105 For the selection of the operating link 29 one end of this link remains in the notch of the selecting member 13 so that upon the engagement of its associated cam therewith the contact spring 45 will be allowed to disengage contact 47 so that an open circuit condition will be established with the line. A condition similar to that just described will take place upon the engagement of the cam individual to the operating link 31 associated with the selecting member 15.

110 Following the engagement of the associated cam with the operating link 32, the cam individual to the operating link 33 causes the bail 34 to be lifted as the other end of this link is fulcrumed on the stationary member 17, thereby closing the con-

fact between contact spring 45 and contact 47 for transmitting a releasing impulse over the line 61. Just prior to the completion of the cycle of the rotation of the shaft 39 5 the cam associated with the member 52 engages the projection thereof, thereby lifting the projecting portion 56 out of engagement with the notches 50 or 51, and, in turn, permitting the setting up of a new 10 selection.

In order to prevent letters from being repeated should a key lever be depressed for a period longer than the time required for the shaft 39 with its associated cams to 15 complete one cycle, the member 22, having an inclined surface, is arranged just above the stop 21 so that should the key lever be held down the stop arm 43 will stop against the inclined surface until the key lever has 20 been released, at which time it will move into engagement with the stop 21.

Although the invention has been described in connection with a particular structure, it is, of course, obvious that many 25 other adaptations thereof may be made without departing from the spirit and scope of the present invention.

What is claimed is:

1. A telegraph transmitter comprising a 30 series of selecting elements, manually actuated means operative to directly set said elements in various combinations, a plurality of pivoted members extending horizontally beyond the ends of said selecting 35 elements and arranged to be fulcrumed on a surface thereof, a transmitting contact, and means for rotating said pivoted members about said selecting elements as a fulcrum to effect the actuation of said contact 40 in accordance with the setting of said elements.

2. A telegraph transmitter comprising a 45 series of selecting elements, each having a notch arranged near its end, means for actuating said selecting elements in various combinations, a plurality of members, one individual to each of said elements and having a free end arranged to engage a surface of said elements beyond the notch 50 therein, means for actuating the members which have their free ends engaging a surface of said elements, and a switch contact operated in accordance with the actuation of said members.

55 3. A telegraph transmitter comprising a series of actuating members, a plurality of selecting elements, each having a notch arranged near its end, means for selectively moving said elements to either bring said 60 notch into or out of registry with the free end of said actuating members, a transmitting contact, and means cooperating with said members for actuating said contact in accordance with the setting of said elements 65 with respect to said members.

4. A telegraph transmitter comprising a plurality of notched code bars, key levers for actuating said code bars in various combinations, a single set of selecting elements conditioned for operation due to the movement of said code bars, a transmitting contact, and mechanical means operating directly on said selecting elements for actuating said contact in accordance with the setting of said code bars. 70 75

5. In combination, a series of selecting elements, a selectable element individual to each of said selecting elements, means for positioning said selecting elements in predetermined combinations, a single transmitting contact, a distributor normally tending to rotate, and means operated directly and immediately upon the operation of any one of said selecting elements for permitting the rotation of said distributor whereby 80 85 said contact is actuated in accordance with the setting of said selecting elements.

6. In combination, a series of selecting elements, a selectable member individual to each of said selecting elements, means for positioning said selecting elements in predetermined combinations for conditioning said members for operation, a single transmitting contact, a distributing mechanism 90 95 cooperating with said members for causing the operation of said transmitting contact in accordance with the setting of said selecting elements, and means operated directly and simultaneously with the operation of said selecting elements for permitting the 100 rotation of said distributing mechanism.

7. In combination, a series of selecting elements, a selectable member individual to each of said selecting elements, means for positioning said selecting elements in predetermined combinations to condition said selectable members for operation, a single transmitting contact, a distributing mechanism comprising a series of cams normally tending to rotate, said cams engaging the selected ones of said selectable members for 110 115 causing the operation of said transmitting contact in accordance with the setting of said selecting elements, a mechanical stop for preventing the rotation of said cams, and means operated simultaneously with the operation of said selecting elements for moving said stop to release said cams for rotation.

8. A telegraph transmitter comprising a series of key levers, a plurality of selecting elements operated in various combinations in accordance with the depression of said key levers, a transmitting contact, means individual to each of said selecting elements for controlling the actuation of said contact, a mechanical distributor normally tending to rotate cooperating with said individual means for effecting the operation of said contact, means common to said key levers 120 125 130

and operated upon the depression of any one thereof, and means operated directly and simultaneously with the operation of said common means for releasing said mechanical distributor.

9. A telegraph transmitter comprising a series of key levers, a plurality of selecting elements operated by said key levers, a transmitting contact, an all-mechanical distributing mechanism for actuating said contact in accordance with the setting of said selecting elements, and means controlled by the depression of any one of said key levers for preventing the continued operation of said distributing mechanism should a key lever be depressed for a period longer than the normal cycle of operation of said distributing mechanism.

10. In combination, a series of selecting elements, a selectable element individual to each of said selecting elements, means for positioning said selecting elements in predetermined combinations, a single transmitting contact, a distributor, a stop arm associated with said distributor for normally preventing the rotation thereof, and an all-mechanical means operated simultaneously with said selecting elements for freeing immediately said stop arm for rotation whereby said contact is actuated by said distributor in accordance with the setting of said selecting elements.

11. A transmitter for start-stop printing telegraph systems having a rotatable con-

tact actuating member to transmit a start impulse followed by a predetermined number of selecting impulses comprising a plurality of key levers, a series of selecting bars selectable in accordance with the operation of said key levers and operated directly by said rotatable contact actuating member for effecting the transmission of the selecting impulses, and means effective when a key lever is held operated for a period longer than that required to transmit the selecting impulses for preventing the rotation of said contact actuating member.

12. A transmitter for start-stop printing telegraph systems comprising an intermittently rotating shaft, a plurality of actuating members disposed about said shaft at different angular positions, a plurality of key levers, a series of selecting bars movable in accordance with the operation of said key levers, impulse transmitting means operated by said actuating members in accordance with the setting of said selecting bars, and means effective should a key lever be held operated for a period longer than the time required to transmit a predetermined number of impulses for preventing the rotation of said shaft and said actuating members.

In witness whereof, I hereunto subscribe my name this 10th day of November A. D., 1921.

HARRY PFANNENSTIEHL.
